CLAIM

The ornamental design for a grill drip pan, as shown and described.

DESCRIPTION

FIG. 1 is a front top perspective view of a grill drip pan showing my new design;

FIG. 2 is a back top perspective view thereof;

FIG. 3 is a front bottom perspective view thereof;

FIG. 4 is a front view thereof;

FIG. 5 is a back view thereof;

FIG. 6 is a left view thereof;

FIG. 7 is a right view thereof;

FIG. 8 is a top plan view thereof; and,

FIG. 9 is bottom plan view thereof.

The broken lines show portions of the grill drip pan and form no part of the claimed design.

1 Claim, 9 Drawing Sheets
